DESIGN FOR A COMBINED CHILD'S PLAY TABLE AND SEAT OR THE LIKE

Clarence A. Mathisson, Chicago, Ill.

Application October 30, 1943, Serial No. 111,538

Term of patent 7 years

(Cl. D33—14)

To all whom it may concern:

Be it known that I, Clarence A. Mathisson, a citizen of the United States, residing in the city of Chicago, county of Cook, State of Illinois, have invented a new, original, and ornamental Design for a Combined Child's Play Table and Seat or the like, of which the following is a specification, reference being had to the accompanying drawing, forming a part thereof.

Fig. 1 is a perspective view of a combined child's play table and seat or the like, showing my new design, and

Fig. 2 is a top plan view thereof.

I claim:

The ornamental design for a combined child's play table and seat or the like, substantially as shown.

CLARENCE A. MATHISSON.
